CHANCE CONTROLLED ELECTRICAL GAME

Charles J. Haumersen, Racine, Wis.

Application April 27, 1954, Serial No. 425,896

3 Claims. (Cl. 273—135)

This invention relates to a game, and especially to a game utilizing electricity as the means to indicate the plays.

The purpose of this game is to provide a game of amusement that combines the element of uncertainty as well as that of observation.

An object of this invention is to provide a game embracing the element of chance.

Another object is to provide a game embracing the element of observation as a factor in winning the game.

Another object of this game is to employ electricity as the means of indicating the results of the various plays.

Further objects and advantages of the invention will be apparent from a consideration of the following detailed description taken in connection with the accompanying drawings wherein a satisfactory embodiment of the invention is shown. However, it is to be understood that the invention is not limited to the details disclosed, but includes all such variations and modifications as fall within the spirit of the invention.

The physical details of the game will be first described and then the mode of playing the game will be explained.

Referring to the drawings;

Fig. 1 is a plan view of the game in the process of being played.

Fig. 2 is a section taken at 2—2 of Fig. 1, and slightly enlarged.

Fig. 3 is a diagrammatic development showing the circuit.

Referring to Fig. 1 of the drawing, 10 is a case of wood or other suitable material, and in this instance is square and of a suitable depth to accommodate the necessary equipment.

A playing panel 12 of non-conducting material forms the top of case 10, and fits in a rabbeted portion at 14, so that panel 12 is flush with the top edge of case 10. Panel 12 can be glued or otherwise secured to the rabbeted portion 14.

A plurality of radially-positioned holes 16 are provided in panel 12. In this instance there are sixteen radial rows of six holes each, having a total of ninety six holes.

Each corner of panel 12 is provided with a prod receptacle designated 18, 20, 22, and 24, and which are of a conventional type.

Grouped about the center of panel 12, in this instance, are four signal lamp units 26, 28, 30, and 32. These units are of the conventional type commercially available and are clearly shown in Figs. 1 and 2. In this instance, the signal lamp units have removable caps provided with the colored lenses usually furnished with these units. For the purpose of this game, the colors are Yellow, Blue, Green, and Red, also indicated as Y, B, G, and R in the drawings, and description.

Units 26, 28, 30, and 32 are identical, so the description thereof will be confined to unit 26 shown in Figs. 1 and 2.

A bulb 34 of the conventional type is provided in the bayonet-slotted socket 36, and a yoke 38 is provided

2

with means for threading it on the body 40, so as to securely assemble the lamp unit in a suitable hole in the panel 12. An insulating washer 42, and a button 44 completes the signal lamp unit.

5 A sub-panel 46 of non-conducting material is fitted within the case 10 as shown in Fig. 2, and is positioned in contact with the underside of panel 12.

Prod receptacles 18, 20, 22, and 24 have bodies 48 as shown in Fig. 2, and which extend a suitable distance 10 through sub-panel 46 so that a nut 50 can be threaded thereon, thus holding the sub-panel securely in place under panel 12.

Sub-panel 46 is provided with a plurality of contact members 52 aligned with each of holes 16 of panel 12. Contact members 52 are rivets, preferably of copper or any other suitable material, or any suitable means may be provided to establish an individual contact at the bottom of each hole 16. Contact members 52 are fitted in suitable holes in sub-panel 46 so that when the latter is assembled against the panel 12, there will be a contact member 52 forming the bottom of each hole.

The novel electrical circuit embraced in this game is partially shown in Fig. 2, and diagrammatically in Fig. 3. A source of current of 110 to 115 volts, in this instance, is supplied through wire 54 which passes through a bushing 56, which fits a hole 58 in case 10. It is appreciated that dry batteries may be employed as the source of current, but such substitution would be well known to those skilled in the art, and would not amount to invention.

In this instance it is necessary to employ a transformer 60 in order to reduce the voltage to 10 to 12 volts, which is a convenient one and suitable for use with the lamp units and the buzzer. Transformer 60 is conveniently mounted in a suitable place in case 10. The buzzer 62 provides the audible signal means, in this instance and is mounted in the case 10 in a suitable place.

Fig. 2 shows the circuit connected to the contact members 52, and represents a typical section through one of the sixteen radial groups of holes. There are six contacts in each of the radial groups making a total of ninety six contacts. For reasons which will appear later, each lamp unit is connected to nineteen contacts 52, at random as shown in Figs. 1 and 2. The arrangement of the various contacts, and their identification is shown by reference characters Y, B, G, and R, which represent Yellow, Blue, Green and Red, respectively. Fig. 2 indicates the typical arrangement in a radial row in which two contacts are arranged to light the Yellow lamp unit 26. For the purpose of this description, unit 26 is provided with a Yellow lens. It is to be understood that there are other contacts 52 connected with unit 26, having a total of ninety-six as indicated in Fig. 1. Fig. 2 shows a contact R connected to the Red unit 32, and a contact G connected to the unit 30, the units 30 and 32 not being shown in Fig. 2. The circuit from the contacts identified as Y in Fig. 2 are connected to the shell 36 of unit 26.

Also provided at random are twenty contacts 52, designated A, two of which are shown in Fig. 2. Contacts 60 A are connected to terminal 64 of buzzer 62, as are all contacts which are designated A.

Terminal 66 of transformer 60 is connected by a wire to a terminal 68 of prod receptacle 18 and also to similar terminals on prod receptacles 20, 22, and 24. Terminal 65 70 is connected by a wire to terminal 72 of buzzer 62, and to contact button 44 of lamp unit 26, and also to the corresponding button of each of units 28, 30, and 32.

Fig. 3 diagrammatically shows the circuit connecting the various contact members 52 to their respective lamp units, and to the audible signal buzzer 62.

It is clear that so far, the circuit is open and will not function. A prod 74 of a conventional type obtained

commercially provides the means of closing the circuit. Prod 74 comprises a length of wire 76 of a length to permit reaching from the prod receptacles to any one of the holes 16. A plug portion 78 is secured to wire 74 and is a friction fit in the hole of each of the prod receptacles 18, 20, 22, and 24. The opposite end of wire 76 is provided with a prod 80 sufficiently small to enter holes 16 freely and to make contact with contacts 52. Prod 80 is secured in electrical contact with wire 76, and a handle 82 of fiber or similar material is provided as a convenient means of holding the prod while playing the game.

A prod 74 can be provided for each player, therefore, one is inserted in each prod receptacle, 18, 20, 22, and 24 as a matter of convenience.

In order to prevent tampering with the equipment and the circuit in case 10, a bottom panel 84 is rabbeted in place as shown in Fig. 2, and fastened with screws or other suitable means.

The circuit as mentioned above is connected to the various contact members 52, at random. The random arrangement is intentionally void of any order and therefore the groups of contact members 52, forming each quarter of panel 46, result in various arrangements. The random arrangement is shown in Fig. 1, where the holes 16 are identified by letters Y, B, G, R, and A, which letters designate the circuit to which the particular contact member 52 is connected. As shown in Figs. 1 and 3, all contacts lettered R are connected to lamp unit 32. All contacts lettered Y are connected to lamp unit 26. All contacts lettered B are connected to lamp unit 28. All contacts lettered G are connected to lamp unit 30; and all contacts lettered A are connected to the buzzer 62.

From the above description, and the drawings, it will be clear that if plug portion 78 of prod 74 is connected, for instance, in prod receptacle 18, and prod 80 is inserted at random in a hole 16, as indicated in Fig. 3, the circuit will be closed, either a lamp will light or the buzzer 62 will be actuated.

A group of holes 86 is provided adjacent each prod receptacle. In this instance twelve holes are a sufficient number to make the game interesting.

A plurality of play indicators 88 having dowel portions 89 fitting holes 86, are provided, one for each hole 86, or twelve indicators adjacent each prod receptacle 18, 20, 22, and 24. Indicators 88 are in groups of different colors to agree with the colors of the lamp-unit lenses.

This game is designed to be played with four players, each player having a station at a prod receptacle 18, 20, 22, and 24. Each player chooses a color to represent him, and places his play indicators 88, of his color, in holes 86 adjacent his station. Normally, the lamp-unit nearest to his station has a lens that corresponds to his color. Fig. 1 shows a game in the process of being played; six indicators having been placed in various holes 16.

When starting to play the game, a player inserts his prod 80 into a hole 16 at random, touching the contact member 52 associated therewith, in a manner as shown in Fig. 2. The circuit connected to the particular contact touched will determine the lamp to be lit. If the prod lights the lamp of the person playing at the moment, he removes an indicator 88 from its hole 86, and inserts in the hole 16 where the indication was made. If the player lights the lamp of another player, he quickly tries another hole and continues until he touches a contact that actuates the buzzer. When this happens he relinquishes his turn to the next player who proceeds to play in a like manner. The first player to place all of his indicators in hole 16 wins the game. The game can continue so as to determine which players finish second, third or fourth.

It is obvious that as so far described, the game is one of chance, in that there is no means of knowing which

contact will light the desired lamp, or actuate the buzzer. However, it is possible, by observing the plays of the other players, to gain an advantage over them by exercising the ability to observe which colors appear when they touch the various contacts. In this way, a careful observer can know beforehand which holes light his lamp, or which hole contacts the buzzer. In this way a player can avoid contacting the buzzer, thereby prolonging his turn, and thereby prevail over his opponents, who may be less observant.

If it should happen that some players establish a pattern of play by memorizing the various holes, it is merely necessary to unscrew the colored caps of the lamp units and interchange them, one for the other. In this way a new arrangement will result.

Another variation in playing this game is possible. This variation is played with two players, each one choosing two colors as their playing colors. This variation requires more attention to the ability of observing the lights as they flash on.

The above being a complete description of an illustrative embodiment of the invention, what is claimed as new and desired to be secured by Letters Patent of the United States is:

1. An electrical game having a plurality of player stations, comprising a panel of non-conducting material provided with a plurality of perforations, a sub-member of non-conducting material having an individual contact means in alignment with each of said perforations, an audible signal means, a prod receptacle at each of said stations, a plurality of differently-colored lamps centrally positioned on said panel, a lamp of one color representing each station, a power supply comprising a first and a second conductor, said first conductor connected to each of said receptacles, a plurality of mutually-independent leads connected to said second conductor, each one of said leads connected to one of said lamps and to a plurality of said contact means at random, an electrical connection between said second conductor and one terminal of said audible signal means, an electrical connection between the other terminal of said audible signal means to the remaining contact means, and prod means for each player, one end of each being connected to a prod receptacle, each player in turn inserting the other end of said prod in one of said perforations at random, thereby either actuating said audible signal means or energizing one of said lamps, and play scoring means of the color representing each player, inserted in said perforations by him to indicate the color of the lamp corresponding to his station if and when it is energized when contacting a specific contact means.
2. An electrical game having a plurality of player stations, comprising a panel of non-conducting material provided with a plurality of perforations, an individual contact means in alignment with each of said perforations, an audible signal means, a prod means at each of said stations, a plurality of colored lamps positioned on said panel, one color for each station, a power supply comprising a first and a second conductor, said first conductor connected to said prods, a plurality of mutually-independent leads connected to said second conductor, each one of said leads connected to one of said lamps and to a plurality of said contact means at random, an electrical connection from said second conductor to one terminal of said audible signal means, a connection from the other terminal of said audible signal means to the remaining contact means, said prod being inserted by each player in turn in one of said perforations at random, thereby either actuating said audible signal means or energizing one of said lamps, and scoring means representing his color being inserted in said perforations by each player if his lamp is energized by the insertion of said prod by him, thereby indicating the location of the perforation whereby his lamp was energized.
3. An electrical game having a plurality of player

stations, comprising a panel of non-conducting material provided with a plurality of perforations, a contact means in alignment with each of said perforations, an audible signal means, a prod receptacle at each of said stations, a plurality of colored lamps, a lamp of one color for each station, a power supply comprising a first and a second conductor, said first conductor connected to said receptacles, a plurality of separate leads connected to said second conductor, each one of said leads connected to one of said lamps and to a plurality of said contact means at random, a connection from said second conductor to one terminal of said audible signal means, a connection from the other terminal of said audible signal means to the remaining contact means, and prod means at each station one end of which being connected to each prod receptacle, the other end being inserted

in one of said perforations at random by each player in turn, thereby either actuating said audible signal means or energizing one of said lamps, and identifying means inserted in said perforations by each player to indicate the perforation associated with the contact whereby his lamp was energized when said contact means was contacted by said prod.
